OF CHICAGO, ILLINOIS, A CORPORATION OF DELAWARE

WIRE-TYING MACHINE

Application filed October 1, 1928. Serial No. 309,396.

The present invention pertains to automatic wire tying machines of the type in which the wire is tensioned, twisted and cut in successive operations.

5 One object of the invention is to provide a machine of the type described which will effect a predetermined number of twists in the wire upon one throw of the hand lever but may be so operated with the lever as to effect 10 feet as many additional twists as desired before the cutting takes place.

Another object is to provide such a machine in which the movement of the hand lever in causing the tensioning, twisting and 15 cutting operations is reduced to a minimum.

Still another object is to provide such a machine in which the hand lever, which causes the tensioning to take place when moved in one direction and the twisting to 20 take place when moved in the opposite direction, is relieved of all resistance from the tensioning mechanism after the wire has been tensioned and is being twisted.

Still another object is to provide such a 25 machine in which the cutter blades are pivoted in front of the line of cut and sheer toward the rear ends of the slots in the holding yokes.

Still another object is to provide such a 30 machine in which the holding yokes are shiftable toward and away from each other to shorten the twist when fine wire is used and are readily removable without disturbing the cutters to permit replacement with yokes 35 having narrower slots for the wire.

Numerous other objects and advantages 40 will be evident to those skilled in the art upon a full understanding of the construction, arrangement and operation of the improved wire tying machine.

One form of the invention is presented herein for the purpose of exemplification, but it will of course be appreciated that the invention is susceptible of embodiment in other 45 structurally modified forms coming equally

within the comprehensive scope of the claims.

In the accompanying drawings:

Fig. 1 is a plan view of a wire tying machine embodying the several features of the 50 invention;

Fig. 2 is a front view of the same;

Fig. 3 is a horizontal section, taken on the line 3—3 of Fig. 2;

Fig. 4 is a vertical section, taken on the line 55 4—4 of Fig. 2;

Fig. 5 is a vertical section, taken on the line 5—5 of Fig. 2;

Fig. 6 is a vertical section, taken on the line 6—6 of Fig. 2; and

Fig. 7 is a plan view of the wire twist produced by the machine.

The machine shown in the drawings includes a wire tensioning mechanism, a wire twisting mechanism and a wire cutting mechanism, which instrumentalities are operated in the order mentioned by the manipulation of a single hand lever. In the starting position of the machine, the hand lever is in the forwardly oblique position shown. 70 When the hand lever is swung rearwardly from that position, the tensioning mechanism functions, and, when it is swung forwardly from its rearmost position, first the twisting mechanism, and then the cutting 75 mechanism, functions.

The hand lever consists of two side arms 10 which are connected at their outer ends by a handle 11 and are secured at their inner ends to a shaft 12 which is journaled in two 80 spaced bearing brackets 13 attached to a flat generally rectangular base plate 14. The hand lever is limited in both its forward movement and its rearward movement by lugs 15 on the inner ends of the arms 10 which 85 engage with front and rear stops 16 on the brackets 13.

The tensioning mechanism consists of two rearwardly converging shafts 17 which are journaled in bearing brackets 18 attached to 90

the base plate 14. Arms 19 are secured to and extend downwardly from the rear ends of the shafts 17 and carry rollers 20 which engage with cams 21 on the inner ends of the arms 10. When the hand lever is swung rearwardly from its forwardly oblique position, the cams 21 force the rollers 20 in opposite directions, and the rollers, acting through the arms 19, cause the shafts 17 to turn in opposite directions. Arms 22 are secured to and extend downwardly from the shafts 17 adjacent the front ends of the same, and carry springs 23 which press against arms 24 which are pivoted to and extend downwardly from the front ends of the shafts. The arm 24 on the left side of the machine carries an arc-shaped wire guiding block 25 which is concentric with respect to the axis of the shaft on which the arm is pivoted and is provided with a notch 26 into which one end of the wire to be tensioned is hooked after being reversely bent to fit the notch. The arm 24 on the right side of the machine carries a similarly shaped and arranged wire guiding block 27, and also carries a spring-pressed wire gripping cam 28 which acts on the other end of the wire against a lip 29 on the arm and is provided with a finger piece 30.

When the tensioning shafts 17 are rotated by the means above described, the lower ends of the resiliently yieldable arms 24 to which the ends of the wire are fastened move away from each other and place the loop of wire encircling the object to be tied under tension, the amount of which tension is determined by the resistance to compression of the springs 23. When the hand lever, in being swung rearwardly to tension the wire, reaches its rearmost position, projections 31 on the lower ends of the arms 19 ride behind shoulders 32 on rearwardly spring pressed latches 33 which are pivoted at 34 to the base plate 14, whereupon the arms 19 are held against return movement and the cams 21 are relieved from the pressure of the rollers 20. After the twisting operation has been completed and the cutting operation is being performed, which occurs when the hand lever approaches its foremost position, studs 35 on the inner ends of the arms 10 engage with slides 36 which are pivoted at 37 to the inner ends of the latches 33 and retract the shoulders 32 on the latches out of engagement with the projections 31 on the arms 19. The shafts 17, after being released in the manner just described, are returned to their normal positions again by springs 38, being controlled in their return movement by supplemental cams 39 on the inner ends of the arms 10 which engage with the rollers 20 and allow the shafts 17 to reach their normal positions only when the hand lever has been swung upwardly after the cutting operation into its normal forwardly oblique position.

65 The twisting mechanism consists of a radially slotted twisting pinion 40 through which the ends of the wire to be twisted extend in lapped relation. The pinion is provided with slotted end trunnions 41 which are journaled in slotted bearing members 42, and the bearing members are detachably secured to the base plate 14 at the center of the front of the same. Two slotted wire holding yokes 43 are detachably secured to the base plate 14 at opposite sides of the bearing members. The yokes 43 prevent the lapped ends of the wire from turning beyond those points during rotation of the twisting pinion, and may be shifted toward or away from the pinion to vary the closeness of the twist in the wire to the extent desired, being secured to the base plate by screws 44 which extend downwardly through apertures 45 which are elongated in the direction of adjustment. The pinion 40 is rotated by a gear 46 which is journaled on the shaft 12 and is rotated in one direction when the hand lever is swung forwardly by an outwardly spring-pressed pawl 47 which is pivoted at 48 to an arm 49 secured to the shaft 12 and engages with any one of several studs 50 on one side of the gear. The gear is prevented from rotating in the opposite direction by means of an inwardly spring-pressed pawl 51 which is pivoted at 52 to a bracket 53 attached to the base plate and engages with any one of the studs 50. When the hand lever is swung from its rearmost position to its foremost position, two complete twists are imparted to the overlapped ends of the wire by the twisting pinion. If three or more complete twists are desired, it is merely necessary to swing the hand lever rearwardly and then forwardly again before it has reached its fully forward or cutting position on the first stroke, whereupon either one or two additional twists may be imparted on the second stroke depending upon the extent to which the hand lever is swung rearwardly before being swung forwardly.

The cutting mechanism consists of two stationary blades 54 which are attached to and project forwardly from the brackets 13 into positions alongside the yokes 43, and two upwardly spring-pressed blades 55 which are pivoted at their front ends to the sides of the front ends of the blades 54 and extend rearwardly at an upward inclination between the blades 54 and the stationary guides 56 attached to the blades 54. The blades 54 are slotted beneath the lower edges of the blades 55 in register with the slots in the yokes 43 and receive the lapped ends of the wire extending through the yokes. The lower edge of the blade 55 at the left side of the machine is so shaped as to cut only the rearmost strand of wire, while the lower edge of the blade 55 at the right side of the machine is so shaped as to cut only the front strand of wire. At the completion of the twisting operation, the

5 rear ends of the blades 55 are depressed by lugs 57 on the inner ends of the arms 10 and the ends of the wire fastened to the tensioning arms 24 are cut off, producing a finished 10 twist such as that shown in Fig. 7. The pivotal connections between the blades 54 and 55 consist of bolts 58 which, because of their accessible positions, may be conveniently tightened or loosened to adjust the sheering 15 action of the blades.

The operation of the machine, briefly summarized, is as follows:

15 The machine is placed upon the box or other object to be bound with wire, and the hand lever, if not already in the forwardly oblique position shown in the drawings, is swung into that position to place the various mechanisms in their normal positions. One end of the wire to be tied is hooked into the notch 26 in 20 the wire guiding block 25 at the left side of the machine and is passed under such block through the aligned slots in the cutting blades 54, the holding yokes 43 and the twisting pinion 40. From the slots the wire is 25 passed around the object, back through the slots again, and then under the wire guiding block 27 at the right side of the machine into engagement with the gripping cam 28. The machine is then held firmly by a conveniently 30 arranged handle 59 attached to the left side of the base plate 14, and the hand lever is swung into its rearmost position, causing the overlapped ends of the wire to be drawn in opposite directions to properly tension the loop of 35 wire about the object. When the hand lever reaches its rearmost position, the latches 33 interlock with the projections 31 on the arms 19 to hold the tension on the wire and relieve the cams 21 on the inner ends of the arm 10 40 from further duty. The hand lever, being then free from the resistance offered by the tensioning mechanism, is swung forwardly, and the pawl 47, which assumes the dotted line position shown in Fig. 5 in the rearmost 45 position of the hand lever, engages with one of the studs 50 on the gear 46, rotates the gear, and causes the pinion 40 to impart two complete twists to the overlapped wire portions between the yokes 43. The twisting operation 50 is completed just before the hand lever reaches its foremost position, and, when the hand lever is swung through the last part of its forward movement, the lugs 57 on the inner ends of the arms 10 depress the rear 55 ends of the blades 55 and sever the excess portions of the wire fastened to the tensioning arms 24. The last part of the forward movement of the hand lever, in addition to effecting the cutting operation, brings the studs 35 60 on the inner ends of the arms 10 into engagement with the slides 36 connected with the latches 33, causing the latches to release the projections 31 on the arms 19 and allow the arms 24 to return to their normal positions. 65 Should more than two complete twists be de-

sired in the wire, it is merely necessary to swing the hand lever back again after the twisting operation and before the cutting operation, whereupon one or more additional twists may be made in the wire before the hand lever is swung into its foremost position to effect the cutting operation.

I claim:

1. In a wire tying machine, a wire twisting pinion, means for rotating the pinion, and 75 two wire holding yokes which are arranged at opposite ends of the pinion and are shiftable toward or away from the pinion whereby to vary the closeness of the twist.

2. In a wire tying machine, a wire twisting 80 pinion, means for rotating the pinion, two wire cutting blades which are arranged at opposite ends of the pinion, and two wire holding yokes which are positioned alongside the blades and may be readily removed without disturbing the blades.

3. In a wire tying machine, a tensioning mechanism, a twisting mechanism, a cutting mechanism, and a single hand lever for operating all of said mechanisms, said lever extending obliquely forward in the normal position of the various mechanisms and being movable first rearwardly and then forwardly to effect the tensioning, twisting and cutting operations.

4. In a wire tying machine, a twisting mechanism, a cutting mechanism, a hand lever for operating said mechanisms, and connections between the hand lever and said mechanisms which cause the twisting mechanism to operate when the lever is moved through one angle and the cutting mechanism to operate when the lever is moved through another angle and which permit the lever to be moved two or more times through the first or twisting angle before being moved through the cutting angle, whereby to impart as many twists as desired to the wire.

5. In a wire tying machine, a frame, a wire twisting pinion, means for rotating the pinion, two wire cutting blades which are arranged at opposite ends of the pinion and are pivotally mounted at their front ends to the frame to shear rearwardly, and means for moving the blades.

6. In a wire tying machine, a slotted wire twisting pinion, two slotted wire holding yokes at opposite ends of the pinion, two shafts at opposite sides of the yokes, means for rotating the shafts in opposite directions, downwardly extending tensioning arms on the shafts, wire-engaging members on the lower ends of the arms, and arc-shaped wire guides for holding the wire down in the plane of the slots in the pinion and yokes when the wire-engaging members move upwardly in being swung outwardly upon rotation of the shafts.

7. In a wire tying machine, a wire tensioning mechanism, a wire twisting mechanism,
